UNITED STATES PATENT OFFICE.

SVEND HANSEN, OF BROOKLYN, NEW YORK, ASSIGNOR TO BIRMINGHAM IRON FOUNDRY, OF DERBY, CONNECTICUT, A CORPORATION.

QUICK RELEASE FOR BRAKE-BANDS.

1,360,634.

Specification of Letters Patent. Patented Nov. 30, 1920.

Application filed March 25, 1919. Serial No. 284,950.

To all whom it may concern:

Be it known that I, SVEND HANSEN, a citizen of the United States, residing at Brooklyn, in the county of Kings and State of New York, have invented a new and useful Improvement in Quick Releases for Brake-Bands; and I do hereby declare the following, when taken in connection with the accompanying drawings and the characters of reference marked thereon, to be a full, clear, and exact description of the same, and which said drawings constitute part of this application, and represent, in—

Figure 1 a broken side view of my improved quick-release for brake-bands, showing the band in engagement with a drum.

Fig. 2 an end view of the releasing mechanism.

Fig. 3 an enlarged side view of the releasing mechanism in the closed position.

Fig. 4 a similar view in the open position.

This invention relates to an improvement in quick releasing mechanism for use in connection with brake-bands particularly applied to winding or drawing drums. In drums for winding various material such, for instance, as thin rolled metal, the brake-band is applied to the drum so as to regulate the speed at which the drum shall run. This brake consists of a band suitably lined and fixed at one point and connected to a nut mounted on a rotatable shaft which may be operated from any convenient point so that by drawing the nut inward, the strap will be drawn against the drum so as to apply friction thereto, or if moved in the opposite direction, will release the band, and reduce the friction. It is sometimes desirable to be able to quickly release the band, and the object of this invention is to provide a latch in connection with the band whereby the tension on the band may be immediately released without adjusting the nut; and the invention consists in the construction hereinafter described and particularly recited in the claims.

In carrying out my invention I show a brake-band 5 provided with a suitable lining 6 and extending over a drum or roller 7 into engagement with a loop 8. The lower end of this loop is pivotally connected with the sides of a latch 9 which in turn is pivoted to a nut 10 mounted on a shaft 11 which extends to any desired point where it

may be provided with a hand wheel 12 by 55 which the shaft may be turned. As herein shown, the shaft is supported in bearings 13, and in the shaft are universal couplings 14 which may be employed or not as occasion requires. The latch 9 is provided with 60 a handle 15, and the nut is provided with a stop-pin 16 against which the latch will rest when it is turned into the locked position at which time the latch stands directly 65 in line with the loop 8. When the latch 9 is turned down as shown in Figs. 1 and 3 of the drawings, the latch is in line with the loop, and the length of the brake-band is such that it will have slight bearing on the drum. If more tension is desired, the shaft 70 will be turned to cause the nut to travel inward which will draw the brake-band with greater force against the drum. Should, however, it be desirable to quickly release 75 the band, it is only necessary to trip the latch, as shown in Fig. 4 of the drawings, which immediately releases the tension of the brake-band on the drum.

I claim:—

1. The combination with a brake-band, of 80 a loop connected with one end thereof, a latch with which the loop is pivotally connected, and a relatively fixed member with which the latch is pivoted.

2. The combination with a brake-band 85 fixed at one end and connected with a loop at the opposite end, a traveling nut, a latch pivotally connected with said nut, said loop being pivotally connected with the sides of the latch.

3. The combination with a drum, of a 90 brake-band extending over said drum one end of the band connected with a fixed point, and the other end connected with a loop, a shaft, a nut mounted on said shaft, a latch 95 pivotally connected with said nut, the said loop pivotally connected with the sides of the said latch whereby when the latch is turned downward it will draw the loop downward and shorten the band.

In testimony whereof, I have signed this specification in the presence of two subscribing witnesses.

SVEND HANSEN.
